ROLAND JAMES SULLY, OF CAVERSHAM, READING, ENGLAND, ASSIGNOR TO
HERBERT MERTON, OF CAVERSHAM, READING, ENGLAND.

DRIVING MECHANISM OF RADIATOR-FANS AND WATER-IMPELLERS FOR MOTOR- VEHICLES AND THE LIKE.

1,366,295.

Specification of Letters Patent. Patented Jan. 18, 1921.

Application filed April 21, 1920. Serial No. 375,582.

To all whom it may concern:

Be it known that I, ROLAND JAMES SULLY, a subject of the King of England, residing in Caversham, Reading, England, have invented certain new and useful Improvements in the Driving Mechanism of Radiator-Fans and Water-Impellers for Motor-Vehicles and the like, of which the following is a specification.

This invention lies in improvements in or relating to the driving mechanism of radiator fans and water-impellers for motor vehicles and the like. One object is to provide a more simple construction of the combined drive for the radiator-fan and water-impeller when these are mounted co-axially so that a pulley mounted on the fan serves also to drive the impeller.

It has already been proposed to mount a radiator fan on the same spindle as a helical or other water-impeller for the radiator of a motor-vehicle, such spindle being generally driven by a pulley mounted thereon, and in such cases a gland is provided between the water-impeller and the fan to prevent leakage of water from the impeller chamber, and a bearing is provided either combined with or separate from this gland.

According to the present invention a radiator-fan and impeller drive wherein the impeller, and the fan with its driving pulley, are rigidly mounted on opposite ends of the same spindle to form one rotating unit, is characterized by the rotating parts being supported at the impeller end by a bearing surrounding the spindle and at the fan end by a single-race ball-bearing in the plane of the driving pulley. Thus only two bearings are provided: the single-race ball-bearing in the plane of the driving pulley takes the whole of the lateral pull of the belt so that no bending moment is applied to the spindle and the second bearing adjacent to the impeller holds the whole of the parts steadily in line, without however having to bear any appreciable load.

Preferably a stuffing-box is provided on the spindle between the two bearings. A very compact construction is thus provided in which although the bearings are well spaced, the overall length of the spindle is not great and yet sufficient room is easily

provided for access to and adjustment of the stuffing-box.

To these ends, the invention consists in the construction, arrangement and combination of parts described hereinafter and pointed out in the claims—

The accompanying drawing represents, mainly in longitudinal section, one embodiment of this invention.

A radiator fan 1 is mounted on or formed integral with a cup 2, which may conveniently have a flange 3 forming one rim of a driving pulley, the other rim 4 being screwed on to the cup 2. The cup 2 is secured to one end of a driving spindle 5, which, at its opposite end, carries a water-impeller 6. This impeller is disposed in an impeller chamber 7 which forms part of the fixed framework and of the water circulation system.

As shown in the drawing, a bearing is formed within the cup 2, which surrounds and embraces a fixed bearing-member 8, which also forms a part of the fixed framework and which embraces the spindle 5, but need not be a tight fit thereon.

A single-race ball-bearing 9 is disposed between the cup 2 and the fixed bearing-member 8. The ball-bearing may be held in position on the fixed member by a lock-nut 10, and similarly the ball-bearing 9 and the removable pulley member 4 may be held in position in relation to the cup 2 by means of a lock-nut 11.

A gland 12 of a stuffing-box is disposed in the fixed framework at the end of the impeller chamber 7 through which the driving spindle 5 passes. It will be seen that this gland 12 is well separated from the bearing-member 8. The result is that if any wear should take place in the bearing, the effect of that wear upon the gland would be minimized. As a matter of fact, with the ball-bearing external to the fixed bearing-member 8, it is easy to make adjustments to compensate for any wear that may take place. Lubricators 13, 14 may be provided for the gland-bearing and the fan-bearing respectively.

One of the chief features of this invention lies in the arrangement of the bearing for the fan drive end of the spindle, such that

the lateral pull of the belt acts in the plane of the single-race ball-bearing, so that the spindle is not subjected to bending stresses, whereby wear and tear is reduced to a minimum.

It will be understood that the details of arrangement and construction may be modified within the scope of the claims without departing from this invention.

10 What I claim as my invention and desire to secure by Letters Patent is:—

1. In a water-cooling system, the combination with a water-chamber having a bearing, a driving spindle extending through said bearing, and an impeller carried by said spindle in said water-chamber, of a bearing-support that is mounted on the water-chamber and surrounds said spindle, a single-race ball-bearing spaced away from the water-chamber, and mounted on the outside of said bearing-support, and a rotary fan having a pulley integral with its hub secured on the other end of said spindle and arranged to embrace and operate on said ball-bearing, said pulley being situated in the same plane as said ball-bearing, substantially as described.

2. In a water-cooling system, the combination with a water-chamber having a bearing, a driving spindle extending through said bearing, and an impeller carried by

said spindle in said water-chamber, of a bearing-support that is mounted on the water chamber and surrounds said spindle, a stuffing-box for said spindle arranged in the wall of said water-chamber intermediate said bearing and said bearing-support, a single-race ball-bearing spaced from the water-chamber and mounted on the outside of said bearing-support, and a rotary fan having a pulley integral with its hub secured on the other end of said spindle and arranged to embrace and operate on said ball-bearing, said pulley being situated in the same plane as said ball-bearing, substantially as described.

3. In a water-cooling system, the combination with a water chamber having a bearing, a driving spindle extending therethrough, and an impeller carried by said spindle in the water chamber, of a bearing support on the water chamber and surrounding said spindle, a bearing effective on said support in a single plane extending diametrically of said spindle, a fan having a positive connection with said spindle, and a pulley secured to said fan, said pulley enclosing said bearing and disposed in the plane thereof, substantially as described.

In testimony whereof I affix my signature.

ROLAND JAMES SULLY.
